(57) **CLAIM**

The ornamental design of an insole packaging, as substantially shown and described.

DESCRIPTION

FIG. 1 is a right side perspective view of an insole packaging in accordance with the present invention;
FIG. 2 is a left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is the perspective view of FIG. 1 with an insole article packaged therein, the insole article shown in broken lines and forming no part of the claimed design.
The portions of the insole packaging shown in broken lines form no part of the claimed design.
